WINDOW SASH LOCK

Alexander Zebrowski, Stamford, Conn.

Application October 29, 1937, Serial No. 171,777

2 Claims. (Cl. 70—90)

The present invention relates to window sash locks and has for its primary object to provide a device of this character adapted to lock both the upper and lower sliding sash of a window 5 against movement when either in a closed or partly open position.

A further object is to provide a sash lock embodying push button actuating means for operating the lock to a locking position and key controlled means for returning the lock to its unlocked or normal position.

Another object is to provide a sash lock mechanism embodying a toothed member attached to each of the sash and slidably mounted bolts carried by the window frame and movable into and out of the path of said toothed members for securing the sash against movement in one direction, said toothed members being arranged to freely ride over the bolts during an opposite movement of the sash to permit uninterrupted movement of the sash in said opposite direction.

A still further object is to provide a sash lock embodying a main double headed bolt for the respective upper and lower sash operable in toothed channel members carried by the sash and said bolt and channel members cooperating to limit raising and lowering movement of the sash within a predetermined range and said bolts further embodying auxiliary bolts movable 20 with the main bolt as a unit and also movable independently of said main bolt and cooperating with the teeth of said channel members to secure the sash against movement in one direction while permitting movement thereof in an opposite direction within the limits of movement controlled by said main bolt.

Other objects and advantages reside in the details of construction and operation as more fully hereinafter described and claimed, reference being had to the accompanying drawings forming part hereof wherein like numerals refer to like parts throughout, and in which.

Fig. 1 is a vertical fragmentary sectional view through a pair of sash members showing the lock 45 in position relative thereto,

Fig. 2 is a fragmentary side elevational view of the sash and lock,

Fig. 3 is a sectional view taken on a line 3—3 of Fig. 1,

Fig. 4 is a rear elevational view of the lock casing,

Fig. 5 is a longitudinal sectional view through the lock casing,

Fig. 6 is a longitudinal sectional view taken 55 on the line 6—6 of Fig. 5,

Figs. 7 and 8 are vertical sectional views taken respectively on the lines 7—7 and 8—8 of Fig. 5,

Fig. 9 is a longitudinal sectional view taken on a line 9—9 of Fig. 5,

Fig. 10 is a perspective view of the bolt locking plate,

Fig. 11 is a perspective view of the locking dog for the locking plate, and

Fig. 12 is a detail of the main and auxiliary bolts with parts shown in section.

Referring now to the drawings in detail, wherein for the purpose of illustration I have disclosed a preferred embodiment of the invention, the numeral 5 designates the lower sash of a window and 6 the upper sash, which are slidably 15 mounted in channels 7 and 8 respectively of a window frame 9.

Along one side edge of each sash is secured a channel member 10 having its ends closed as at 11 and provided with teeth 12 along one longitudinal side edge.

A lock casing 13 is secured to the window frame, the outer surface of the lock being provided with a rib 14 in alignment with the parting strip 15 of the window frame and forming a continuation 25 of said strip.

A spring retracted member 16 is slidably mounted in the casing, said member including a block 17 slidable on a pin 18 fixed in a chamber 19 at the rear of the casing and upon which pin 30 is mounted a coil spring 20 for retracting the block inwardly of the casing. The outer end of the block is formed with a pair of main spaced bolts 21 movable into and out of position within the respective channel members 10 and in spaced 35 relation from the opposite sides of the rib 14 whereby to engage the ends 11 of the channel members to limit raising and lowering movements of the sash when the bolt is in a projected position.

A pair of auxiliary bolts 22 are also carried by the block 16, each of said auxiliary bolts embodying stems 23 slidable in openings 24 formed in the block and normally projected outwardly by springs 25. The auxiliary bolts are positioned 45 laterally with respect to the main bolts 21, as more clearly shown in Fig. 1 of the drawings, and bridge the space between the main bolts 21 and the rib 14 at opposite sides of said rib. The toothed edge 12 of the channel member is movable between one of the main bolts 21 and the adjacent side of the rib 14 for engagement by the auxiliary bolt 22, and it will be apparent from an inspection of Fig. 2 of the drawings that the teeth 12, having one edge horizontal as shown 55

at 26, engaging said auxiliary bolt, will prevent movement of the sash in one direction, whereas the opposite edge of the teeth are inclined as shown at 27 to enable the teeth to ride past the bolt to permit movement of the sash in an opposite direction within the limitation of the ends of the channel.

5 A lever 28 is pivotally mounted upon a pin 29 within the casing, one end of the lever being provided with a lateral extension 30 engaging the block 16 for projecting the bolt outwardly, the opposite end of the lever being engaged by a button 31 extending outwardly through an opening in the casing 13.

15 A locking plate 32 is slidably mounted in a guide 33 within the casing, said locking plate being provided with a shoulder 34 against which a leaf spring 35 engages for yieldably urging the plate in a position for overlying the inner ends 20 of the main bolts 21 to secure the bolts in projected position.

25 Key controlled means is provided for releasing the locking plate 32 and embodies a cam 36 on one edge of the plate 32 with which the key 37 inserted in the keyhole 38 is engageable. One or more key-controlled locking dogs 39 is also provided for securing the plate against releasing movement, each of said dogs being pivoted at one end on a pin 40 and having a shoulder 41 formed adjacent a slot 42 at its opposite end, said shoulder abutting a lug 43 projecting from the plate 32 to secure the plate against releasing movement. The shoulder is held in engagement with the lug by a leaf spring 44 having one end attached to the dog 39 and its opposite end bearing against one wall of the casing. One longitudinal edge of the dog is disposed in the path of the key 37, whereby upon the manipulation of the key in a direction as shown by the arrow in Fig. 5, the dog will be raised to release the shoulder 41 from engagement with the lug 43 and upon a continued movement of the key the lug 43 will enter this slot 42 during the releasing movement of the plate 32. The plate 32 is provided along one longitudinal edge with a notch 46 to accommodate the bolt 21 when the locking plate is released, whereupon the spring 20 will serve to retract the main and auxiliary bolts.

30 In the operation of the device with the bolt retracted the sashes will be free to move to their full extent and upon depressing the button 31, the bolts will be projected for engaging the channel member 10, the main bolts 21 being disposed in the path of the ends 11 of the channel member to limit movement of the sash within a predetermined range and the teeth 12 engaging the auxiliary bolts 21, locking the sash against movement in one direction and by reason of the spring mounting of the auxiliary bolts the teeth will be permitted to ride over the same to enable movement of the sash in an opposite direction within the limitations of the channel member.

35 In order to prevent unauthorized removal of

the lower sash 5 while the same is partly raised, which ordinarily could be accomplished by the removal of the molding strip 47, I provide a stop plate 48 secured to the frame in the channel 7 of the lower sash and having an angular outstanding flange 49 which overlies the front side of the sash, as shown in Fig. 3, and which prevents forcing the sash inwardly.

40 It is believed the details of construction and manner of operation of the device will be readily understood from the foregoing without requiring further detailed explanation.

45 What I claim is:

1. A window sash lock for upper and lower sliding sashes, each having a channel member positioned in the guide channels of the window frame, each of said channel members being closed at each end and having a toothed longitudinal edge, said sash lock comprising a lock mechanism attached to the frame and embodying a pair of spring retracted main bolts movable into and out of said channel members and engageable with the ends of said members to limit movement of the sash, spring mounted auxiliary bolts extending laterally from the main bolts and movable with the main bolts as a unit, said auxiliary bolts being disposed in the path of the toothed edge of said channel members for securing the sash against movement in one direction within the limitations of said channel members, spring actuated bolt locking means normally held in one position by the retracted bolts and operable to releasably secure the bolts in projected position, a manually depressible member operatively engaged with the main bolts for projecting the same, and key manipulated means for releasing the bolt locking means.

2. In a window sash lock for upper and lower sashes, a channel member positioned in the guide channels of the window frame, each of said channel members being closed at each end and having a toothed longitudinal edge, said sash lock comprising a lock mechanism attached to the window frame and embodying a pair of spring retracted main bolts movable into and out of said channel members and engageable with the ends of said members to limit movement of the sash, auxiliary bolts disposed laterally of the main bolts yieldingly mounted for movement in one direction independently of the main bolts and movable with the main bolts as a unit, said auxiliary bolts being disposed in the path of the toothed edge of said channel members for securing the sash against movement in one direction within the limitations of said channel members, and yieldably movable to permit movement of the sash in the opposite direction without movement of the main bolts from projected position, means for moving the main bolts to projected position, means for locking the main bolts projected, and key manipulated means for releasing the bolt locking means.

ALEXANDER ZEBROWSKI.
